JACK CONTROL DEVICE FOR KNIT GOODS CIRCULAR DOBBY

Jaime Font Trabal, Avenue Generalísimo Franco, 608,
Barcelona, Spain

Continuation of abandoned design application Ser. No.
245,024, Apr. 17, 1972. This application Jan. 28, 1974,
Ser. No. 436,957

Claims priority, application Spain Oct. 16, 1971

Term of patent 14 years

Int. Cl. D15—06

U.S. Cl. D47—5

FIG. 5.

FIG. 1 is a front elevational view of a jack control device for knit goods circular dobbies showing my new design;

FIG. 2 is a side elevational view thereof;

FIG. 3 is an elevational view of the other side;

FIG. 4 is a rear elevational view;

FIG. 5 is a top plan view; and

FIG. 6 is a bottom plan view.

This is a continuation of design application Ser. No. 245,024, filed Apr. 17, 1972, and now abandoned.

I claim:

The ornamental design for a jack control device for knit goods circular dobbies, as shown and described.
